UNITED STATES PATENT OFFICE

151,512

DESIGN FOR A BEAD COLLAR OR SIMILAR ARTICLE

Jean Harber, Weehawken, N. J., now by change of name Jean Harber Goldstein

Application April 2, 1945, Serial No. 118,818

Term of patent 7 years

(Cl. D45—16)

To all whom it may concern:

Be it known that I, Jean Harber, a citizen of the United States, residing at Weehawken, in the county of Hudson and State of New Jersey, have invented a new, original, and ornamental Design for Bead Collar or Similar Article, of which the following is a specification, reference being had to the accompanying drawings, forming a part thereof.

In the drawings:

Fig. 1 is a perspective view of the bead collar or similar article, showing my new design.

Fig. 2 is an enlarged edge view of a portion of the bow element taken along the line 2—2 of Fig. 1, and

Fig. 3 is an enlarged detail view of the collar portion taken along the line 3—3 of Fig. 1.

The dominant features of my design for a bead collar or the like reside in the portions shown in full lines on the drawing which portions are repeated in reverse on the half shown in broken lines.

I claim:

The ornamental design for a bead collar or similar article, as shown and described.

JEAN HARBER GOLDSTEIN.
